UNITED STATES PATENT OFFICE.

JAMES H. TAYLOR, OF NEW YORK, N. Y., ASSIGNOR TO THE AMERICAN LAUNDRY MACHINERY COMPANY, OF CINCINNATI, OHIO, A CORPORATION OF OHIO.

FLAT-WORK IRONER.

Application filed November 8, 1921. Serial No. 512,444.

This invention relates to flat work ironers and particularly to that class including an ironing bed and one or more padded rolls cooperating with the bed.

5 Heretofore it has been customary in machines of this type to provide an ironing bed having a plurality of curved ironing faces, forming troughs, which receive the peripheries of padded ironing rolls mounted in 10 suitable bearings guided in the frame and forced toward the bed by a plurality of springs arranged in a member adapted to be raised and lowered to bring the rolls into and out of engagement with the bed. These 15 machines heretofore have been used for flat work of substantially one thickness and have not been used with any degree of success in ironing articles having buttons and of uneven thicknesses for the reason that the 20 pressure due to the weight of the rolls is so great that the buttons are broken and good work is not produced, especially in machines utilized in commercial laundries.

The present invention aims to overcome 25 the disadvantages accompanying the use of these machines for general ironing purposes by providing means for suspending each ironing roll in a manner to cause it to float, so that each ironing roll will bear on the 30 bed with the necessary degree of pressure to properly iron articles of varying thicknesses and leave the buttons unharmed. The invention is also designed to prevent undue packing or hardening of the padding on the 35 rolls by reason of the fact that the rolls do not bear with unlimited pressure upon the ironing faces of the bed.

Other features of the invention will be brought out more clearly in the following 40 description, drawings and claims.

Referring to the drawings, Fig. 1 is a side elevation of the machine with parts broken away; Fig. 2 is a section upon the line 2—2, Fig. 1; Fig. 3 is an enlarged view partly in 45 section and partly in elevation of Fig. 2; and Fig. 4 is a sectional view upon the line 4—4, Fig. 3, some parts appearing in elevation.

In the arrangement shown in the drawings, the frame comprises side members 1, each provided near its upper edge with roll bearing guides 2 as shown in Fig. 1. These frame members are secured together by any suitable means and by the hollow ironing 55 bed 3 which is adapted to be supplied with

steam or other heating medium through the pipe 4, there being another pipe, not shown, for establishing circulation. This is a structure which is common to many types of flat work ironers. Mounted in the bearing 60 guides 2 and sliding therein are roll bearings 5 receiving the trunnions 6 of the ironing rolls 7. The guides are usually made with parallel sides and the bearings are square or rectangular so as to slide nicely in these 65 guides, the sliding movement of the bearings being toward and from the bed. Each of the roll bearings 5 is provided with an upwardly extending ear 8 provided with a slot 9 and a spring pilot 10, the latter extending upwardly. The slot 9 receives a pin 11 passing through the sides of a pressure bar 12 extending the full length of the machine and common to all of the rolls. Engaging each spring pilot 10 is the lower 70 end of a pressure applying spring 13 having its upper end engaging the pilot on a pressure block 14 adapted to be engaged by the end of a pressure screw 15 extending through the top of the pressure bar. A 75 check nut 16 holds this screw and hence the adjusting or pressure applying spring 13 in any desired position.

Each roll bearing is provided with a 80 downwardly extending spring pilot 17 adapted to engage in the lower roll supporting spring 18. In the case of each roll this pressure spring 18 nests in a socket 19 arranged in a spring yoke 20. This spring yoke in each side of the socket 19 is provided 85 with a pair of ears 21 each receiving a pin 22 passing through an eye 23 of a lower spring adjusting bolt 24. As above indicated there are two of the adjusting bolts 90 and the upper ends thereof are threaded and pass through lugs 25 forming a part of a bracket or support 26 secured to a stationary machine part, such as the ironing bed, by means of bolts 27. Each of the bolts 24 is provided with a nut 24' to provide adjustment of the lower springs, so that said springs may be so positioned relative to the ironing bed by the supporting yokes 20 that the ironing rolls 7 will just contact with said bed when no ironing pressure is being 100 produced by the upper springs 13.

The pressure bars 12, one on each side of the machine, are given their upward and downward movement by links 28 and 29, each of which is provided with an eccentric 105

strap 30 engaging eccentrics 31 arranged on transverse shafts 32. Each of these shafts is provided with a worm gear meshing with worms 34 adapted to be driven by gear 35 which meshes with a pinion 36 arranged on a hand wheel shaft 37. When the hand wheel is rotated the pressure bars are raised and lowered to bring the rolls 7 into and out of engagement with the ironing bed.

10 This pressure mechanism for the bars 12 is of a well known construction.

In adjusting the machine the pressure is relieved from the upper springs 13 and the lower springs are adjusted or positioned to 15 carry the weight of the rolls. The upper springs are then adjusted to the proper tension to produce the desired ironing effect between the rolls and the bed without creating sufficient pressure to break buttons on 20 articles passing through the machine.

From the foregoing it will be seen that the rolls float, as it were, in the machine and exert the proper effect without any undue pressure upon the work, thereby preventing 25 the breaking of buttons and the undue hardening or packing of the padding on the rolls.

Having described my invention, I claim:

1. In an ironing machine, an ironing member, a superposed padded ironing roll 30 operating with said ironing member, means for moving said ironing roll into and out of ironing position, supporting means having a constant position relative to said ironing member, means mounted upon said supporting 35 means for supporting said ironing roll in ironing contact with but with no pressure on said ironing member when all the ironing pressure hereinafter referred to is removed from the ironing roll, and yielding means effective upon said ironing roll for producing the desired yielding ironing pressure upon the work as it passes between said ironing member and said ironing roll.

2. In an ironing machine, an ironing member, a superposed padded ironing roll 45 operating with said ironing member, means for moving said ironing roll into and out of ironing position, supporting means having a constant position relative to said ironing member, yielding means mounted upon said supporting means for supporting said ironing roll in ironing contact with but with no pressure on said ironing member when all the ironing pressure hereinafter referred to 50 is removed from the ironing roll, and yielding means effective upon said ironing roll for producing the desired yielding ironing pressure upon the work as it passes between said ironing member and said ironing roll.

3. An ironing machine, comprising a 55 frame, an ironing bed, a plurality of padded ironing rolls co-operating with said bed and movable toward and from said bed, supporting means having constant position relative 60 to said bed, means mounted upon said sup-

porting means for supporting said ironing rolls in ironing contact with but with no pressure on said ironing bed when all the ironing pressure hereinafter referred to is removed from the ironing rolls, and pressure 70 means movable toward and from said ironing bed and effective upon said ironing rolls for producing the desired yielding ironing pressure upon the work as it passes between said ironing bed and said ironing rolls, said 75 pressure means and said ironing rolls being connected together so that movement of said pressure means away from said bed effects like movement of said ironing rolls.

4. An ironing machine, comprising a 80 frame, an ironing bed, a plurality of padded ironing rolls co-operating with said bed and movable toward and from said bed, supporting means having constant position relative to said bed, means mounted upon said supporting 85 means for supporting said ironing rolls in ironing contact with but with no pressure on said ironing bed when all the ironing pressure hereinafter referred to is removed from the ironing rolls, and pressure 90 means movable toward and from said ironing bed and effective upon said ironing rolls for producing the desired yielding ironing 95 pressure upon the work as it passes between said ironing bed and said ironing rolls, said pressure means and said ironing rolls being connected together so that they move together toward and from the ironing bed.

5. In an ironing machine, an ironing member, a superposed padded ironing roll 100 co-operating with said ironing member, means for moving said ironing roll into and out of ironing position, yielding means, supporting means for said yielding means adjustable to such a position that the latter will support 105 said ironing roll in ironing contact with but with no pressure on said ironing member when all the ironing pressure hereinafter referred to is removed from the ironing roll, means for maintaining said supporting 110 means in such adjusted position, and yielding means effective upon said ironing roll for producing the desired yielding ironing pressure upon the work as it passes between said ironing member and said ironing roll.

6. An ironing machine, comprising an ironing bed, an ironing roll co-operating with said bed, supporting means for said roll, means for moving the roll toward and from the bed, means for determining and fixing a definite position of said roll supporting means relative to the bed in which position the roll on said supporting means contacts with the bed but with no pressure thereon when all the ironing pressure hereinafter referred to is removed, and means effective upon said roll for applying ironing pressure between the roll and the bed.

7. An ironing machine, comprising an ironing bed, an ironing roll co-operating with 130

said bed, yielding supporting means for said roll, means for moving the roll toward and from the bed, means for determining and fixing a definite position of said yielding roll

sure hereinafter referred to is removed, and means effective upon said roll for applying ironing pressure between said roll and the bed.

5 supporting means relative to the bed in which position the roll on said supporting means contacts with the bed but with no pressure thereon when all the ironing pres-

In testimony whereof I hereby affix my signature.

JAMES H. TAYLOR.
